K. T. BUTTERY

2,578,878

TRAY TYPE CARTON

Filed July 15, 1947

UNITED STATES PATENT OFFICE

2,578,878

TRAY TYPE CARTON

Kenneth T. Buttery, Kalamazoo, Mich., assignor
to Sutherland Paper Company, Kalamazoo,
Mich., a corporation of Michigan

Application July 15, 1947, Serial No. 761,107

5 Claims. (Cl. 229—35)

1

The main objects of this invention are:

First, to provide a collapsible tray or box formed of an integral blank which may be easily and quickly erected and when erected the walls are interlocked and supported to sustain substantial load.

Second, to provide a collapsible tray or box having the above stated advantages in which the side end walls are supported substantially at right angles to the bottom.

Third, to provide a tray or box having these advantages in which there is very little cut away or waste stock.

Objects relating to details and economies of the invention will appear from the description to follow. The invention is defined in the claims.

A preferred embodiment of the invention is illustrated in the accompanying drawing, in which:

Fig. 1 is a perspective view of a tray or box embodying my invention in erected position.

Fig. 2 is a plan view of the box collapsed or in the flat.

Fig. 3 is an enlarged fragmentary view partially in vertical longitudinal section illustrating engagement of the corner flaps with the side walls.

Fig. 4 is a view similar to Fig. 3 illustrating the manner of engagement of the corner flaps with the side walls.

Fig. 5 is an enlarged fragmentary view in section on line 5—5 of Fig. 3.

Fig. 6 is an enlarged fragmentary view in section on line 6—6 of Fig. 4.

Fig. 7 is a fragmentary inside perspective view of a corner of the box illustrating the relation of the parts when in erected position.

My improved collapsible tray or box comprises a bottom 1, side walls 2, 2, and end walls 3, 3, the side walls being hingedly connected to the bottom along the line 4, 4, and the end walls being hingedly connected to the bottom along the line 5, 5. The end walls have corner flaps on their end edges hingedly connected thereto at 7.

It will be noted that the end walls and their corner flaps are of substantially greater width than the side walls, thus providing a box when erected having the effect of recessed side walls for exposing the contents, the higher end walls protecting the goods particularly when they are wrapped so that the goods may be inspected not only through the top of the box or wrapper but through the recessed sides.

The side walls have diagonally disposed inwardly inclined slits 8 extending from the bottom edges of the side walls in spaced relation to their

2

end edges. The side walls also have in this embodiment of Figs. 1 to 7 inclusive, angled slits 9 extending from the inner edges of the slits 8 in spaced relation to the outer ends and coaction therewith to provide outwardly projecting deflectable tongues 10.

The corner flaps 6 have notches 11 on their side edges with slits 12 extending from the bottoms of the notches, these slits being diagonally disposed in an upwardly inclined relation and providing tongues 13. The corner flaps 6 are separated from the end edges of the side walls by the slits 14, which are aligned with the folding scores 5. The outer edges 15 of the tongue portions of the corner flaps are curved to facilitate their entrance through the slits 8.

In erecting the box, the side walls are erected or swung to erected position and then the end walls erected with the corner flaps angularly disposed on the outer sides of the side walls. As the end walls are swung to erected position, the tongue portions of the corner flaps are inserted through the slits 8 with the result that portions of the bottom edges of the corner flaps are in supported engagement with the bottom and lie within the side walls, other portions of the corner flaps being on the outer side of the side walls and in supporting engagement therewith.

When the box is fully erected, the end walls are in abutting engagement with the ends of the side walls so that the walls are supported in angular relation to the bottom and well adapted to withstand external thrust such, for example, as occurs in wrapping the box. The angle of the corner slits correspond substantially to the angle of the side wall slits so that when the box is erected, the inner edges of the corner flap slits 12 extend longitudinally of and abuttingly engage the outer edges of the diagonal wall slits 8 as shown at 8 and 12 in Fig. 5.

I have illustrated and described my invention as adapted by me to the tray type of box for merchandising food products and the like. I have not attempted to illustrate or describe other embodiments or adaptations which I contemplate as it is believed that this disclosure will enable those skilled in the art to embody or adapt my invention as may be desired.

Having thus described my invention, what I claim as new and desire to secure by Letters Patent, is:

1. A collapsible tray or box formed of an integral blank comprising a bottom and side and end walls hingedly connected thereto, and corner flaps hingedly connected to the ends of the end

walls and foldable on the outer sides of the side walls when they are in erected position, the side walls having diagonally disposed slits spaced from their end edges and extending upwardly and inwardly inclined from their bottom edges, the side walls also having angled slits on the outer sides of and opening to said diagonal slits in spaced relation to their upper ends and providing deflectable upwardly projecting tongues in the side walls, the side edges of the corner flaps being notched and provided with diagonal slits extending inwardly from said notches and providing tongues engageable with the diagonal slits of the side walls, the slits of the corner flaps being substantially parallel to the diagonal slits of the side walls when the box is erected, the inner edges of the corner flap slits engaging the outer edges of the diagonal side wall slits when the box is erected, said inner and outer edges abuttingly engaging each other substantially longitudinally each other above said tongues.

2. A collapsible tray or box formed of an integral blank comprising a bottom and side and end walls hingedly connected thereto, and corner flaps hingedly connected to the ends of the end walls and foldable on the outer sides of the side walls when they are in erected position, the side walls having diagonally disposed slits spaced from their end edges and extending upwardly and inwardly inclined from their bottom edges, the side walls also having angled slits on the outer sides of and opening to said diagonal slits in spaced relation to their upper ends and providing a deflectable upwardly projecting tongues in the side walls, the side edges of the corner flaps being provided with diagonal slits, the slits of the corner flaps being substantially parallel to the diagonal slits of the side walls when the box is erected, the inner edges of the corner flap slits engaging the outer edges of the diagonal side wall slits when the box is erected, said inner and outer edges abuttingly engaging each other substantially longitudinally each other above said tongues.

3. A collapsible tray or box formed of an integral blank comprising a bottom and side and end walls hingedly connected thereto, and corner flaps hingedly connected to the ends of the end walls and foldable on the outer sides of the side walls when they are in erected position, the side walls having diagonally disposed slits spaced from their end edges and extending upwardly and inwardly inclined from their bottom edges, the side walls also having angled slits on the outer sides of and opening to said diagonal slits in spaced relation to their upper ends and providing deflectable upwardly projecting tongues in the side walls, the side edges of the corner flaps being notched and provided with diagonal slits extending inwardly from said notches and providing tongues engageable with the diagonal slits of the side walls, the slits of the corner flaps being substantially parallel to the diagonal slits of the side walls when the box is erected, the inner edges of the corner flap slits engaging the outer edges of the diagonal side wall slits when the box is erected with the end walls in supported engagement with the end edges of the side walls, and with portions of the bottom edges of corner flaps in supported engagement with the bottom, said inner and outer edges abuttingly engaging each other substantially longitudinally each other above said tongues.

edges of corner flaps in abutting engagement with the bottom within the side walls, said inner and outer edges abuttingly engaging each other substantially longitudinally each other above said tongues.

5. A collapsible tray or box formed of an integral blank comprising a bottom and side and end walls hingedly connected thereto, and corner flaps hingedly connected to the ends of the end walls and foldable on the outer sides of the side walls when they are in erected position, the side walls having diagonally disposed slits spaced from their end edges and extending upwardly and inwardly inclined from their bottom edges, the side edges of the end flaps being provided with diagonal slits engageable with the diagonal slits of the side walls, the slits of the corner flaps being substantially parallel to the diagonal slits of the side walls when the box is erected, the inner edges of the corner flap slits engaging the outer edges of the diagonal side wall slits when the box is erected with the end walls in supported engagement with the end edges of the side walls and with portions of the bottom edges of corner flaps in supported engagement with the bottom, said inner and outer edges abuttingly engaging each other substantially longitudinally each other above said tongues.

5. A collapsible tray or box formed of an integral blank comprising a bottom and side and end walls hingedly connected thereto, and corner flaps hingedly connected to the ends of the end walls and foldable on the outer sides of the side walls, the side walls having upwardly extending slits closed at the lower ends thereof and spaced from the end edges of the side walls, the side edges of the flaps being provided with open ended slits extending inwardly from said side edges and being disposed substantially parallel to the slits 40 of the side walls when the box is erected, the inner edges of the corner flap slits engaging the outer edges of the side wall slits when the box is erected with the end walls in supported engagement with the end edges of the side walls, said inner and outer edges abuttingly engaging each other substantially longitudinally each other adjacent their upper ends.
